(57) CLAIM

The ornamental design for a head for golf club, as shown and described.

DESCRIPTION

FIG. 1 is a toe side, bottom and rear perspective view of a head for golf club;

FIG. 2 is a heel side bottom and rear perspective view thereof;

FIG. 3 is a bottom plan view thereof;

FIG. 4 is a rear elevational view thereof;

FIG. 5 is a front elevational view thereof;

FIG. 6 is a toes side elevational view thereof;

FIG. 7 is a toe side, bottom and rear perspective view of a second embodiment of the head for golf club;

FIG. 8 is a heel side bottom and rear perspective view of FIG. 7;

FIG. 9 is a bottom plan view of FIG. 7;

FIG. 10 is a rear elevational view of FIG. 7;

FIG. 11 is a front elevational view of FIG. 7;

FIG. 12 is a toes side elevational view of FIG. 7;

FIG. 13 is a toe side, bottom and rear perspective view of a third embodiment of the head for golf club;

FIG. 14 is a heel side bottom and rear perspective view of FIG. 13;

FIG. 15 is a bottom plan view of FIG. 13;

FIG. 16 is a rear elevational view of FIG. 13;

FIG. 17 is a front elevational view of FIG. 13; and,

FIG. 18 is a toes side elevational view of FIG. 13.

The broken line showing of the unclaimed portions of the head for golf club is included for the purpose of illustrating environment and forms no part of the claimed design. The dash-dot-dash lines disclosed adjacent to the claimed design are boundary lines and form no part of the claimed design.

1 Claim, 12 Drawing Sheets
